UNITED STATES PATENT OFFICE.

IRA L. REEVES, OF THE UNITED STATES ARMY.

PROJECTILE AND MEANS FOR DIRECTING THE SAME.

1,295,794.

Specification of Letters Patent. Patented Feb. 25, 1919.

Application filed August 31, 1918. Serial No. 252,252.

(FILED UNDER THE ACT OF MARCH 3, 1883, 22 STAT. L., 625.)

To all whom it may concern:

Be it known that I, IRA L. REEVES, colonel, U. S. Army, a citizen of the United States, stationed at Washington, District Columbia, 5 have invented an Improvement in Projectiles and Means for Directing the Same, of which the following is a specification.

The invention described herein may be used by the Government, or any of its officers or employees in prosecution of work for 10 the Government, or by any other person in the United States, without payment of any royalty thereon.

This invention relates to projectiles and 15 means for directing the same, and refers more particularly to means for cutting military wire entanglements.

The principal object of the invention is to provide a device of the foregoing character 20 whereby a projectile may be hurled at a wire entanglement, the projectile being provided with cutting blades adapted to sever the wires as the projectile contacts therewith.

Another object consists of the provision of 25 means for rotating the blade projectile so that it may be released to travel through wire entanglements, the revolution of the blades making it possible for the projectile to sever the wires of the entanglement when it comes 30 into contact with that objective.

A further object is to provide, in addition to means for rotating the projectile, means for directing and hurling the revolving projectile against the objective, to further increase the speed and effectiveness of the missile.

A still further object is to construct the projectile with a hollow space therein adapted to receive explosive, and to provide therefor 40 a time-fuse, whereby the explosive may be detonated when the projectile comes to rest, or at any predetermined time desired, whereupon the projectile will be ruptured and the pieces thereof projected to further demolish the entanglement or other objectives.

With the foregoing, and other objects in view, the invention comprises the new and useful details of construction and arrangement, which will be fully described herein, 50 illustrated in the annexed drawings, and pointed out more specifically in the appended claims.

In the accompanying drawings, wherein

a simple embodiment of my invention is 55 illustrated, like reference characters refer to like or corresponding parts throughout.

Figure 1 is a side elevation of one embodiment of my projectile in place in a simple device for revolving and directing the same. 60

Fig. 2 is a front elevation of the embodiment shown in Fig. 1.

Fig. 3 is a fragmentary elevation of the device, partly in section, illustrating the means for releasing the projectile from the 65 directing means.

Fig. 4 is a side elevation of one embodiment of my projectile.

Fig. 5 is a detail elevation of one of the projectile-releasing elements carried by the 70 directing means.

Fig. 6 is a sectional detail view of one of the keeper members by means of which the projectile is held in place prior to its release, the view being taken on line 6—6 of 75 Fig. 5.

Referring now to the drawings, the means illustrated for revolving and launching the projectile comprises a catapult consisting of a rectangular base plate 1 having attached thereto spaced-apart bearing pedestals 2 in which is journaled a transverse shaft 3. Pivoted to swing about shaft 3 between the bearing pedestals is a bifurcated lever unit 4, having a transverse hub portion 5 perforated to receive shaft 3 therethrough. The lower end of the lever unit is restricted to form a central arm 6 and one end of a coiled spring 7 is engaged thereto, as by an eye-bolt 8, while the opposite end of the spring is 90 engaged to the base plate by an eye-bolt 9 carried in an up-standing lug 10 on the base plate. Spring 7 is positioned to normally press the lever 4 in a counter-clockwise direction about pivoting shaft 3, for a purpose 95 which will be further explained. The upper end of lever 4 is bifurcated, the lateral arms thereof being designated by numerals 11 and 11', each of which are provided at their outer ends with alined bearings 12 and 12', respectively, carrying stub shafts 13 and 13', each of which shafts carry adjacent their outer ends outside of arms 11 and 11' the respective sprocket gears 14 and 14'.

Fixed to shaft 3, preferably outside of the 100 bearing pedestals, are sprocket gears 16 and 16', in the planes, respectively, of sprocket gears 14 and 14', and sprocket chains 15 and

15' are trained about each of the respective aligned pairs of gears. A balance wheel 17 is carried on shaft 3 and is shown outside of sprocket gear 16'. Cranks such as 18 and 18' are provided on the ends of shaft 3.

Removably fixed between the ends of the aligned stub shafts 13 and 13' and revoluble therewith is a circular projectile 19, the means for effecting the removable engagement between the stub shafts and the projectile comprises sleeves 20 and 20' slidably longitudinally on shafts 13 and 13', respectively, each of the sleeves being splined to their respective shafts to revolve therewith.

5 The inner ends of the sleeves are provided with squared recesses 21 and 21', respectively, into which squared bosses 22 and 22' on opposite sides of the projectile hub are adapted to fit.

0 Means for sliding the sleeves 20 and 20' longitudinally of shafts 13 and 13' comprises slip rings 23 and 23' carried by each of the respective sleeves, to which are pivoted yoked levers 24 and 24'. Levers 24 and 5 24' are fulcrumed adjacent the yoked ends thereof, as at 25 and 25' and springs 26 and 26' are interposed between the levers and the lateral arms 11 and 11', respectively, to normally press the yoked ends of said levers 0 apart, thus normally pressing sleeves 20 and 20' apart to disengage the interposed projectile.

In order to hold the sleeves in engagement with the bosses on the projectile, keepers 27 and 27' are pivoted adjacent their centers on the upper or forward edges of arms 11 and 11', each of said keepers having hooks 28 and 28', adapted to engage the lower free ends of levers 24 and 24', respectively, to hold the levers in the position shown in Fig. 2, wherein the sleeves 20 and 20' are in engagement with the respective bosses 22 and 22'. Keepers 27 and 27' are provided with projecting extensions 29 and 29' positioned to act in the 5 capacity of trip levers, as will be hereinafter fully explained.

The preferred position for loading the projectile into the aforementioned lever unit 4, is illustrated in Fig. 1, this position being maintained by the engagement of a trigger mechanism comprising a bell-crank lever 30 pivoted at the angle between a pair of upstanding ears 31 carried by the base. The vertical leg 32 of the bell-crank is provided 5 with a forwardly extending tooth 33 positioned to engage a rearwardly projecting tooth 34 fixed on the under or rear side of the lever unit in any suitable manner. The horizontal leg 35 of the bell-crank is extended rearwardly in position to be pressed downwardly by the operator to swing the vertical leg 32 rearwardly, thus to withdraw tooth 33 from engagement with tooth 34, allowing the lever unit 4 to be swung in a counter-clockwise direction by a spring 7, as

previously explained. A coil spring 36 is engaged at one end to lever 32, and at the other end to the base plate, whereby leg 32 will be normally urged forwardly into its engaged position.

70 A bumper such as 37 is positioned transversely of the device, the same being mounted at each end to pedestals 2-2. The bumper comprises a contact plate 38 normally held in position by coiled springs 39 interposed between the contact plate and the bumper proper, the bumper unit being positioned in the path of the lever unit when the lever swings in a counter-clockwise direction. Fixed to the ends of bumper 37 are 80 trip arms 40 and 40', said arms being in the path of trip levers 29 carried by the keepers 27 and 27', respectively, engagement between the trip arms and trip levers being effected, preferably just prior to the engagement of 85 the lever unit with the bumper.

85 The projectile 19 comprises a wheel having a hollow rim preferably circular in cross section, about the periphery of which are fixed a plurality of sharpened teeth 42, to provide cutting edges about the periphery of the projectile when revolving in a counter-clockwise direction. The hollow rim is adapted to be filled with explosive and a time-fuse 43 is positioned at any convenient 90 point on the rim, the same having access to the explosive within the rim.

95 In operation, the initial position of my device is as shown in Fig. 1, wherein the lever unit 4 is engaged by the bell-crank 30. Projectile 19 is engaged between sleeves 20 and 20', as previously described, and the teeth 28 and 28' on keepers 27 and 27' are in position to engage 24 and 24', respectively. The time fuse is set to explode the projectile 100 at the desired future time, whereupon the cranks 18 and 18' are rotated in a counter-clockwise direction to thus actuate the projectile, through the medium of gears 16 and 16', chains 15 and 15', gears 14 and 14', 105 shafts 13 and 13', and sleeves 20 and 20'. It will be understood that the revolution of projectile 19 is desired to be at relative great rate of speed, and to this end cranks 18 will be rotated rapidly. It is to be understood 110 that compound gearings may be substituted for the mechanism shown, and that a motor may be applied to shaft 3 to rotate the mechanism, should it be desired to develop greater speed for the projectile. When the 115 desired rate of speed has been attained for the projectile, the horizontal leg 35 of the trigger mechanism will be pressed by the operator, thereby disengaging the lever unit, allowing spring 7 to swing the upper end of 120 the lever forward, the strength of spring 7 being such as to perform this operation very rapidly. As the lever unit swings to an upright position, trip levers 29 and 29' will swing therewith into engagement with trip 125

130

bars 40 and 40', respectively, thereby simultaneously releasing levers 24 and 24', and disengaging the revolving projectile from sleeves 20 and 20'.

- 5 In practice it is preferable for the revolving projectile to travel in a line parallel with the base of the device when the projectile leaves the lever. To this end, the projectile releasing mechanism is positioned 10 to release the projectile when the lever is in a position at right angles to the base, whereupon the projectile will be directed in a line tangent to the arc of the travel of lever 4, thus in a line substantially parallel 15 to the base of the device. Thus the force exerted by the swinging lever unit on the revolving projectile will throw the projectile forward, in addition to the obvious tendency of the projectile to roll on the surface 20 of the ground when gravity has eventually overcome the impetus of the initial force. It will also be obvious that when the projectile reaches its objective, the revolving blades thereon will readily sever the wires 25 of an entanglement, cutting a path therethrough in an obvious manner.

It will be understood that the present embodiment of my device is designed to be operated from a trench and that the vertical plane of travel of the projectile will be at right angles of the transverse shaft 3. In order to adjust the device for change of traverse, it will be necessary to shift the base accordingly. It will be understood 30 that the base may be mounted on a pivot in order that it may be swung for traverse, and that sighting mechanism may be applied thereto, but, since only relative accuracy for such a device is required no such means 35 have been applied to the illustrated embodiment.

Having thus described my invention what I claim as new and desire to secure by Letters Patent is:

45 1. The combination with a projectile in the form of a wheel, means for supporting the projectile, means for imparting rotary motion to the projectile while being supported, means for imparting a forward movement 50 to said projectile and means for releasing said projectile from said support so that the same will be thrown forwardly while still possessing its rotary motion.

55 2. The combination of a projectile in the form of a wheel provided with teeth on its outer periphery, means for supporting the same, means for imparting rotary motion to the projectile while being supported, means for imparting a forward movement 60 to said projectile and means for releasing said projectile from said support so that the same will be thrown forwardly while still possessing its rotary motion.

65 3. The combination of a projectile in the form of a wheel having a hollow periphery

and provided with cutting teeth on its outer surface, means for imparting rotary motion to the projectile while being supported, means for imparting a forward movement to said projectile and means for releasing 70 said projectile from said support so that the same will be thrown forwardly while still possessing its rotary motion.

4. The combination of a projectile in the form of a wheel having a hollow periphery 75 and cutting teeth provided on its outer surface and an explosive carried in said hollow periphery of the wheel, means for supporting the same, means for imparting a rotary motion to the projectile while being supported, means for imparting a forward movement to said projectile and means for releasing said projectile from said support so that the same will be thrown forwardly 80 while still possessing its rotary motion. 85

5. The combination of a projectile in the form of a wheel having a hollow periphery and provided on its outer surface with a plurality of cutting teeth and an explosive substance in said periphery and a time fuse 90 to coöperate with said explosive substance, means for supporting the projectile, means for imparting rotary motion to the projectile while being supported, means for imparting a forward movement to said projectile and means for releasing said projectile from said support so that the same will be thrown forwardly 95 while still possessing its rotary motion.

6. In combination with a projectile circular in form and provided with a plurality of cutting teeth on its outer edge, a base, an arm pivotally supported to said base and means at the outer end of said arm for supporting said projectile, means connected to 100 the means at the outer end of said arm for imparting a rotary motion to said projectile, means for forcing the pivotal arm forwardly and means connected with said arm for releasing said projectile so that the same 110 will be hurled forwardly while said projectile is still revolving.

7. The combination of a projectile in the form of a wheel, a machine for hurling said projectile and rotating the same comprising 115 a base, an arm pivotally mounted in said base and a spring connected with said base and said arm for forcing the outer end of the arm forwardly when said arm is released, means at the outer end of said arm 120 for supporting said projectile, means connected to said supporting means for imparting rotary motion to said projectile and means for withdrawing the support from said projectile when said pivoted arm has 125 been forced to its most forward position by said spring so that said projectile will be hurled forwardly while still possessing its rotary motion.

8. In combination with a projectile in the 130

- form of a wheel provided with cutting edges on its outer periphery, a machine for rotating and hurling the same comprising a base plate, upwardly extending supporting posts, 5 an arm pivoted near its lower end in said supporting posts, said arm bifurcated at its upper portion, bearings formed at the outer ends of said arm and two stub-shafts in said bearings, a crank extending through said 10 supporting posts and said pivoted arm and sprockets mounted thereon, further sprockets mounted on said stub-shafts and chains coöperating with the sprockets on said stub-shafts and said crank to thereby 15 impart a rotary movement to said stub-shafts when the crank is revolved, sockets mounted on the inner ends of said stub-shafts and adapted to normally hold the said projectile and means connected with 20 said sockets adapted to coöperate with means on said supporting posts when the said pivoted arm is moved to its forward position to thereby release the said projectile.
- 25 9. A machine for revolving a projectile and hurling the same in a forward direction comprising a base plate, supporting arms, integral with said base plate, an arm pivotally mounted between said supporting 30 arms and a crank extending through said supporting arms and said pivotal arm and provided with sprockets near its opposite ends, said arm being bifurcated at its upper portion and reduced at its lower portion, stub-shafts suitably mounted at the outer ends of said arm and provided with 35 sockets on their inner ends, and sprockets on their outer ends, connecting said sprockets on the crank so that when said 40 crank is revolved said stub-shafts will also be revolved, the sockets on the inner ends of said stub-shafts arranged to rotate with said stub-shafts and capable of a sliding movement, a wheel like projectile adapted 45 for engagement with said sockets and means connecting with said sockets and said bifurcated arms for normally holding the sockets in their innermost position, means for forcing the pivotal arm in an upward 50 position when said arm is released and means on said supporting arms coöperating with means on said bifurcated arms to force the said sockets apart when said pivotal arm is released to thereby permit the release of 55 said projectile.
10. The combination of a projectile in the form of a wheel and means for rotating and hurling the same, comprising a supporting member, an arm pivotally mounted 60 near its lower end in said supporting member, a crank extending through said supporting member and said pivotal arm, sprockets secured to said crank, a balancing wheel also on said crank said pivotal arm being bifurcated at its upper portion and reduced at 65
- its lower portion, a tension member connected with said supporting member and said pivotal arm, means for normally retaining the pivotal arm in its lowermost position and releasing the said arm to be forced 70 forwardly by said tension member when desired, stub-shafts suitably mounted on the arms of the pivotal arm, and sprockets mounted on the outer ends of said stub-shafts and coöperating with the sprockets 75 on said previously mentioned arm so that the said stub-shafts will be revolved when said crank arm is revolved, socket members slidably mounted on the inner ends of said stub-shafts and adapted to be rotated with 80 said stub-shafts, two levers provided with yoke rings coöperating with said sockets and means for normally holding said sockets in their innermost position, trigger arms secured to the lower portion of said bifurcated arms and adapted to normally hold the said levers in their said position and fingers mounted on the supporting means adapted to coöperate with said triggers when 85 said pivotal arm is released to thereby force 90 the said sockets forwardly on said stub-shafts and thereby release the wheel-like projectile.
11. A machine for rotating and releasing a wheel-like projectile comprising in 95 part a supporting base, an arm pivotally mounted in said base, said arm being bifurcated at its upper end and stub-shafts mounted at the outer ends of said arms, means for revolving said stub-shafts, socket 100 members mounted on the inner ends of said stub-shafts and adapted to rotate with said stub-shafts and also capable of sliding movement on said stub-shafts, levers connected with said sockets and adapted to normally 105 hold said sockets in their innermost position, spring members connected with said levers, for forcing said socket members apart and trigger arms coöperating with 110 said levers for holding the sockets in their innermost position and means for actuating the said trigger arms when said pivotal arm is swung forwardly to cause the socket members to be forced apart to thereby release the projectile.
- 115 12. The combination of a projectile in the form of a wheel, a machine for rotating said projectile and hurling the same in a forward direction, comprising a base, supporting posts arranged at opposite sides of said base, 120 an arm pivotally mounted between said supports and a tension member secured to the lower end of said arm and said base, means for normally holding said arm in a downward position in tension, a crank extending through the lower end of said pivoted arm and said support provided with sprockets 125 near its outer ends, stub-shafts located on the opposite ends of said arm provided with sprockets and adapted to be turned when 130

- said sprockets on said crank are revolved, supporting sockets slidably mounted on said stub-shafts and adapted to be revolved with said stub-shafts to revolve the wheel-like projectile, means for normally holding said supporting sockets in their innermost position to support said wheel, said means comprising trigger arms, and levers coöoperating with said sockets and lever arms, spring 10 members connected with said levers and the pivotal arm and means formed on the supporting member to coöperate with said trigger arms when said pivotal arm is released and moved forwardly, to thereby permit the 15 spring members to force the said sockets apart and thereby release the wheel like projectile.
13. A machine for imparting a rotary movement to a wheel-like projectile and throwing the same forwardly, comprising, a base with supports secured thereto and an arm pivotally mounted in said supports, stub-shafts located at the outer end of said arm and provided with sprockets on their 25 outer ends and sockets on their inner ends and means for revolving said sprockets, a tension member secured to the lower end of said arm and said base and means for normally holding said arm and releasing the same whereby the said tension member will 30 force the said arm upwardly, means secured to the supports for taking up the shock of said arm when said arm is forced forwardly and in contact therewith, means for holding 35 the sockets in their innermost position to thereby support the wheel-like projectile when the same is being revolved, and means for forcing the sockets away from each other when said pivotal arm is forced upwardly
- to thereby release the said wheel-like projectile. 40
14. The combination of a projectile and means for rotating and hurling the same, comprising in part, a projectile in the form of a wheel having a hollow periphery, an explosive in said periphery, a plurality of cutting edges on the outer surface of the periphery, a hub portion provided with outwardly extending lugs, sockets, and the said lugs adapted to fit within the sockets when 45 said wheel is to be revolved, means for revolving said sockets, means for imparting a forward movement to said sockets and means for forcing the sockets apart to thereby release said projectile. 50 55
15. A machine for throwing a projectile, including a base, a lever unit mounted for swinging movement on the base, rotatable projectile supports carried by the lever unit, means for rotating the supports, means for 60 swinging the lever unit to impart a forward movement to the projectile and means for releasing the supports from the projectile.
16. A machine for throwing a projectile, including a base, means carried by the base 65 for imparting a forward movement to a projectile said means including rotatable projectile supports, and means for rotating the supports.
17. A machine for throwing a projectile, 70 including a base, and means carried by the base for imparting a forward movement to the projectile, said means including rotatable projectile supports, means for rotating the supports, and means for releasing the 75 supports at a predetermined position in the movement of the first mentioned means.
